UNITED STATES PATENT OFFICE

2,611,573

LIGHT SUPPORTING MEANS

John C. Young, Pittsburgh, Pa.

Application January 17, 1946, Serial No. 641,694

3 Claims.

176 *Journal of Health Politics*

This invention relates to a lighting means for the interior of hand bags or like portable containers.

An object of the present invention is to provide means for the illumination of the interior of hand bags and similar portable article containing cases.

Another object of the invention resides in the provision of a new article of manufacture in the nature of illuminating means which can be readily built into a hand bag, suitcase or other portable article carrying receptacle or container as the latter are manufactured or which, as an article of manufacture, can be installed in any of such receptacles after their manufacture or use.

A still further object is to provide for the movable location of an illuminating means inside of a hand bag or the like so that in times of darkness in particular contents of the hand bag or the like may be readily located among numerous articles sometimes carried in such article carrying containers or receptacles.

With these and other objects in view, the invention consists in the construction and novel combination and arrangement of parts herein-after fully described, illustrated in the accompanying drawings and pointed out in the claims hereto appended, it being understood that various changes in the form, proportion, and minor details of construction within the scope of the claims may be resorted to without departing from the spirit or sacrificing any advantages of the invention.

In the drawings

Figure 1 is a perspective view of a hand bag in closed position, illustrating in dotted lines one embodiment of my invention applied thereto;

Figure 2 is a fragmentary face view of one wall of a hand bag illustrating one form of my invention applied thereto;

Figure 3 is a transverse sectional view through the hand bag of Figure 1;

Figure 4 is a transverse sectional view on the line 4-4 of Figure 2;

Figure 5 is a transverse sectional view on the line 5-5 of Figure 2;
Figure 6 is a fragmentary view of one wall of

Figure 7 is a transverse sectional view on the hand bag illustrating a modified form of the invention:

Figure 8 is a similar view illustrating another

Figure 9 is a sectional view on the line 9—9.

Figure 9 is a sectional view on the line 9-9 of Figure 8.

5 Referring now more particularly to the accompanying drawings, the reference A indicates generally a hand bag, including a handle 9, sides 10 and 11 and ends 12 and 13 providing a pocket composed of leather or other suitable flexible material and having the usual flexible lining 14 for the side walls and the lower portions of the end walls and bottom of the bag or the like.

10 Relatively narrow frame members 15 and 16 are secured in any suitable manner to the upper edges of the side walls 10 and 11, respectively. These frame members include downwardly extending ends 17 and 18, respectively, which are pivoted or hinged at their free ends, as at 19. 15 said frame members stiffening the upper portion of the hand bag and providing a closable opening 20 for the bag and which opening may be releasably fastened against accidental opening by any well known or suitable manner.

20 The illuminating or lighting means of the present invention, while electrical in nature, does not require intricate wiring or a complicated switch. The lighting means in the present invention is very simple and obviates the use of wiring extended over an area of the interior of the hand bag. To accomplish my purposes, I employ a small self-contained flash light B of any suitable kind now on the market and which includes a battery (not shown), a button or switch operating member 22 of a character to flash the light through the bulb 23a in a well known manner, and remain set for lighting purposes until the button or switch operating member 22 is manually shifted to inoperative position as in a well known or usual way.

25

30

35

In Figures 1 to 5, inclusive, a common flash light B is detachably mounted in the hand bag, either new or old, after manufacture of the bag. One manner of thus mounting the flash light B 40 in the hand bag consists of a safety pin C of common design and of suitable size, secured in the lining 14 adjacent the side wall 10.

A plate 23 of metal or other suitable material is slidably mounted on the rod or arm 24 of the safety pin C, said plate 23 having its upper edge bent or folded loosely about the arm 24 of the safety pin, as at 25, whereby to suspend the said plate 23 from the safety pin. This plate 23 has one end provided with hinge knuckles 26 adapted for pivotal or hinge connection with the hinge knuckle 27 of a metal or other arm 28, there being a hinge pintle 29 effectively swingingly connecting said hinge knuckles together to provide for a swinging movement of said arm 28 across the interior of the hand bag.

The arm 28 carries depending rings or loops

30 and 31 adapted to embracingly receive the flash light B. The plate 23 and the arm 28 constitute a holding framework which is provided at one side with the safety pin C and at the opposite side with rings encompassing the small electric flashlight B. These rings or loops 30 and 31 are preferably resilient or bendable so as to provide for a tight gripping of the flash light and yet, when desired, as when a new battery is needed for the flash light, the latter may be removed and replaced. A new battery can be inserted in the flash light casing without removing the flash light from the rings or loops 30 and 31 by removing the detachable end cap 32 from the flash light casing, if necessary sliding the flash light slightly away from the enlarged inner end a' of the arm 28.

It will thus be seen that by virtue of the slideable mounting of the plate 23 on the arm 24 of the safety pin C, and the hinged connection 26-27-29 between the said plate and the arm 28, that the flash light can be shifted in the hand bag lengthwise thereof and also cross-wise of the bag and also lifted upwardly or outwardly on the arm 28 of the safety pin by reason of the loose sliding connection between the plate 23 and the safety pin arm 24, thereby providing for illumination over various portions of the interior of the hand bag and providing for the use at times, or if desired, of the flash light for lighting purposes outside of the bag by opening the latter and swinging the flash light nearer to the open mouth of the bag, enabling the user in a time of darkness to locate a desired key on a key ring usually carried in a hand bag, as well as aiding in locating a key-hole.

In Figures 6 and 7 there is illustrated a modified form of the invention in which the flash light supporting means differs from that illustrated in Figures 1 to 5, inclusive, and in which the modified supporting means is built into the hand bag as the latter is manufactured. To this end the modified supporting means consists of two plates 33 and 34 riveted together as at 35 on opposite sides of the hand bag lining 14'. The inner plate 33 is provided at its upper edge with hinge knuckles 26' adapted to be coupled by pintle 29 to a hinge knuckle 27' on the plate 21a. To one end of this plate 21a, a relatively short arm 28' is hingedly connected as at 28a. This arm at its outer end has a laterally directed extension 28'' to which is secured in any suitable manner, as soldering or riveting, the usual screw threaded cap a at the inner end of the ordinary flash light and into the socket of cap a the flash light casing can be screwed and unscrewed. In other words, the usual cap at the inner end of the flash light can be removed from the flash light casing and be secured by riveting, soldering or in any suitable manner, to the lateral extension 28'' of the arm 28' and the flash light casing then screwed into said cap whereby to support the flash light.

In the modified form of the invention illustrated in Figures 6 and 7, the flash light has both vertical and horizontal swinging movement in the hand bag as in the first form described. In another modification of the invention, as shown in Figures 8 and 9, the flash light B'' has a longitudinal sliding movement and also has a transverse swinging movement and a vertical swinging movement in the hand bag. For instance, as illustrated in Figures 8 and 9, there are spaced sets of inner and outer plates 36 and 37 riveted at 38 to opposite sides of the lining 14''. A relatively long rod 39 is fixed at its ends in the

5 hangers 40 at the lower ends of the inner plates 36. A plate 41 has its upper edge 42 folded loosely over and around said rod 39, as in Figs. 1 to 5, inclusive, to provide for a sliding movement of said plate 41 longitudinally along said rod.

10 The short arm 43 has a hinged connection 26'' with the plate 41 and the short arm 43 is provided with a short lateral extension 35'', as in Figures 6 and 7, to which the usual flash light casing cap 35'' is secured, as in Figures 6 and 7 to receive exteriorly threaded inner end of the flash light casing B'' as in the modified form illustrated in Figures 6 and 7.

15 Thus, in the form of the invention illustrated in Figures 8 and 9, the flash light can be swung upwardly in a vertical plane toward the mouth of the hand bag and it also has longitudinal movement along the rod 39 as well as a horizontal swinging movement by reason of the hinged connection between the plate 41 and the short arm 43 which carries the flash light.

20 From the foregoing it will be seen that the use of intricate wiring in the hand bag or other portable container is obviated by the use of the common small sized flash light and that the invention is thereby simplified and economical of manufacture either as an original part of a manufactured container or as an article of manufacture for detachable association with a new or worn portable container.

25 What is claimed is:

30 1. Light supporting means for hand bags and the like comprising a substantially flat rectangularly shaped plate-like frame and a conventional safety pin, the latter having opposed substantially parallel arms, the said frame having a turned-over portion at its top edge in the form of a sleeve within which one of the arms of the safety pin is disposed so as to slidably and swingably mount the frame on the pin, the frame being dependently supported by the pin and having a hinge connection at one side edge thereof with an elongated flashlight-supporting arm, and the said arm having at least one ring thereon adapted to surround a portion of a flash light to detachably secure the same thereon, whereby the frame may be swingably and slidably moved on the arm of the pin and the flashlight-supporting arm be moved in an arc relative to said frame.

35 2. Lighting means as defined in and by claim 1 wherein the other of said arms of the conventional safety pin is secured to the interior of a hand bag or the like and thus allowing a swinging movement in a fixed plane of the safety pin and the sliding and swinging movement of the frame on the other arm of the safety pin and the swinging movement in an arc of the flashlight-supporting arm relative to the pin and the frame.

40 3. Light supporting means for hand bags and the like comprising a substantially flat rectangularly shaped frame, the upper edge of which is in the form of a turned-over hollow sleeve that is coextensive in length with the frame and which is positioned on one arm of a conventional safety pin and adapted for sliding and swinging movement relative to the said arm, the frame having a hinge structure substantially coextensive with one side edge thereof, the hinge structure cooperating with the hinge structure of an elongated flashlight-supporting arm, and at least one ring means depending from said flashlight-supporting arm and adapted to extend about a flashlight to secure the same thereto, whereby when

the said light supporting means is pinned within a hand bag or the like the pin may swing about the arm that secures the same to the hand bag and the frame can be both slidably and swingably manipulated on the arm of the pin that carries the same, and the hinged flashlight-supporting arm can be swung on a vertical axis relative to the frame and the pin so that the interior area of the hand bag or the like can be effectively illuminated throughout.
